United States Patent Office

Des. 225,071
Patented Nov. 7, 1972

225,071

EXERCISER OR SIMILAR ARTICLE

Richard I. Proctor, 3201 Orange Grove Ave.,
North Highlands, Calif. 95660

Filed Apr. 27, 1971, Ser. No. 138,015

Term of patent 14 years

Int. Cl. D21—02

U.S. Cl. D34—5

Fig. 2.

Fig. 1.

Fig. 3.

Fig. 4.

FIG. 1 is a front elevational view of an exerciser or similar article showing my new design;

FIG. 2 is a top plan view;

FIG. 3 is a rear elevational view; and

FIG. 4 is an elevational view of one side, the opposite side being substantially similar in appearance.

I claim:

The ornamental design for an exerciser or similar article, as shown and described.
